LOADING AND UNLOADING DEVICE

Domenic Oliva, Lincoln, Calif., assignor of forty
percent to John Puglise, Roseville, Calif.

Application February 29, 1936, Serial No. 66,485

2 Claims. (CL 258—11)

This invention relates to improvements in loading and unloading devices and has particular reference to a device for receiving and depositing articles from any moving vehicle such as a train, airplane and the like.

The principal object is to enable the operator of a vehicle to quickly and safely deposit and pick up containers in which mail, merchandise or other commodities have been placed.

10 A further object is to produce a device which is quickly adjustable to various conditions relative to height or longitudinal placement.

A still further object is to produce a device which is positive in its operation and one which 15 will not cause an impact at the moment of contact between the vehicle and the receptacle holding apparatus.

Other objects and advantages will be apparent during the course of the following description.

20 In the accompanying drawings forming a part of this specification and in which like numerals are employed to designate like parts throughout the same.

Fig. 1 is a front elevation of my apparatus,
25 Fig. 2 is a cross sectional view on the line 2—2 of Fig. 1,

Fig. 3 is an end elevation of the carrier,

Fig. 4 is an end elevation of the carrier looking from the opposite end of Fig. 3,

30 Fig. 5 is a side elevation of Fig. 3,

Fig. 6 is a cross sectional view on the line 6—6 of Fig. 5,

Fig. 7 is a top plan view of the turntable carriage,

35 Fig. 8 is a fragmentary cross sectional view of the vehicle receiving mechanism,

Fig. 9 is a top plan view of Fig. 8,

Fig. 10 is a cross sectional view on the line 13—13 of Fig. 8,

40 Fig. 11 is an end elevation of the receptacle receiver, and

Fig. 12 is an end elevation of my device.

The purpose of my apparatus is to receive from a moving train or airplane, a commodity receptacle and deposit the same in the moving vehicle without shock to the vehicle and to also deliver from the vehicle to a suitable receiving mechanism a similar commodity receptacle in such a manner that the commodities therein will not be injured.

Referring to Fig. 1 the same illustrates a receiving station consisting of a rectangular frame having end pieces 5 and 6 joined by a cross piece 7. There are two of these frames spaced apart and joined by end pieces 9 (see Fig. 2). Verti-

5 cally movable on suitable guide rails is an elevator 8 which may be controlled from a station 11. Mounted upon the elevator is a circular platform 12 which rotatably supports a turntable 13 having a central pivot 14 through which a compressed air line 16 passes. Suspended from the turntable 13 is a carrier 17 which is provided on its inner surface with side rollers 18 and with bottom rollers 19. The bottom of this carrier is open as best illustrated in Figs. 3 and 4. Secured 10 to the bottom of the carrier are guide vanes 21 and bottom plates 22. Projecting through one of the guide vanes is a trigger 23 which controls a valve 24 connected to the air line 16. A pipe 26 extends from the valve 24 to an air cylinder 27. 15 The piston of this cylinder is connected to a pusher plate 28 carried upon guide rods 29. A spring member 31 is secured to the top of the carrier, the purpose of which will be later seen.

The operation of the apparatus thus far described is that, when a vehicle having suitable receiving apparatus passes beneath the carrier, which has been adjusted to the proper position, either to the right or left of Fig. 1 or up or down to accommodate for the varying heights of the receiving vehicle, the action will be that as the receiver passes between the guide vanes 21 the trigger 23 will be moved to open the valve 24 allowing compressed air from the pipe 16 to enter the cylinder 21. This will cause the piston and 20 its connecting rod to push the plate 28 forwardly from the dotted line position of Fig. 6 to the full line position. This will give the commodity receptacle, shown in dotted lines in Fig. 5, an initial movement in the same direction that the receiving vehicle is moving. At the same time the receiving apparatus, to be later described, will pass through the slot in the bottom of the carrier and will pick up the receptacle and push it along the rollers 19 without any apparent shock on the receiving vehicle. As soon as the receptacle passes out of the carrier, its weight will be entirely borne upon the receiving apparatus and in order to prevent the same moving upwardly the spring 31 is 25 provided.

The receiving apparatus is best illustrated in Figs. 8, 9 and 10 and consists of a pair of spaced tracks 32 and 33. These tracks are curved from end to end and have their forward ends projecting above the top of the vehicle which is designated as 30 a whole by the numeral 34. Shoes 36 are mounted at the forward ends of the tracks and are the contact means between the pick-up mechanism and the guide vanes 21 and 22. A receiving receptacle or carriage 37 is mounted upon the tracks 32 and 35 40

45

50

55

- 33 and is provided with two sets of rollers, a forward set 38 and a rear set 39. The forward set travels within a groove formed in the tracks and the rear set travels upon the top of the tracks.
- 5 A cable 41 is connected to the carriage and to a hoisting mechanism designated as a whole by the numeral 42. The cable 41 is used to move the carriage 37 from the dotted line position of Fig. 8 to the full line position of this figure.
- 10 When the carriage is within the vehicle it assumes the dotted line position of Fig. 8. Pivoted to the sides of the carriage are hooks 43 which are adapted to engage pins 44. These hooks are pivoted as at 46 and have their rear ends connected by a saddle 47. A spring pressed plate 48 is pivotally secured to the rear of the carriage, the purpose of which will be presently seen.

As a consequence of this construction, when the vehicle passes beneath the carrier having a commodity receptacle therein, and assuming that the carriage has been elevated to pick up position, the result will be that as the shoes engage the trigger 23 the receptacle will be moved forwardly as above described by the admission of air pressure to the cylinder 27. The plate 48 passing through the opening in the end of the carrier will contact the receptacle and due to the initial movement of the receptacle and the spring action of the plate 48 very little relative movement between the two will take place. As the receptacle drops from the carrier into the carriage the weight thereof will fall upon the saddle 47 pivoting the hooks 43

thus releasing the carriage and due to the incline of the tracks 32 and 33 the same will roll rearwardly to the dotted line position of Fig. 8, at which point the commodity receptacle may be removed.

5

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:—

1. In a device of the character described, the combination with a receptacle holding apparatus and a receptacle receiving apparatus mounted on a vehicle capable of passing beneath said holding apparatus, said receiving apparatus including a carriage supported on tracks on said vehicle and movable on said tracks to a point within said vehicle.

2. In a device of the character described, the combination with a receptacle holding apparatus and a receptacle receiving apparatus mounted on a vehicle capable of passing beneath said holding apparatus, said receiving apparatus including a carriage supported on tracks on said vehicle and movable on said tracks to a point within said vehicle, and means for releasing said carriage for movement on said tracks upon receipt of a receptacle from said holding apparatus.

DOMENIC OLIVA.
